(57) **CLAIM**

The ornamental design for a cutting insert for grooving operations, as shown and described.

DESCRIPTION

FIG. 1 is a perspective view of a cutting insert according to the present invention.

FIG. 2 is a top plan view of the cutting insert of FIG. 1.

FIG. 3 is a left elevation view of the cutting insert of FIG. 1.

FIG. 4 is a front elevation view of the cutting insert of FIG. 1.

FIG. 5 is a right elevation view of the cutting insert of FIG. 1.

FIG. 6 is a perspective view of a second embodiment of a cutting insert according to the present invention.

FIG. 7 is a top plan view of the cutting insert of FIG. 6.

FIG. 8 is a left elevation view of the cutting insert of FIG. 6.

FIG. 9 is a front elevation view of the cutting insert of FIG. 6; and,

FIG. 10 is a right elevation view of the cutting insert of FIG. 6.

The broken lines shown on the side of the cutting insert are for illustrative purposes only and form no part of the claimed design.
